DESIGN FOR A CUP FAVOR

Floyd H. Bartlett, Williamsport, Pa., assignor to
C. A. Reed Company, Williamsport, Pa., a corporation of Delaware

Application January 12, 1934, Serial No. 50,378

Term of patent 7 years

To all whom it may concern:

Be it known that I, FLOYD H. BARTLETT, a citizen of the United States, residing at Williamsport, in the county of Lycoming and State of Pennsylvania, have invented a new, original, and ornamental Design for a Cup Favor, of which the following is a specification, reference being had to the accompanying drawing, forming part thereof.

Figure 1 is a perspective view of a cup favor and Figures 2 and 3 are front and side elevational views, respectively, of the same showing my new design.

I claim:

The ornamental design for a cup favor, as shown.

FLOYD H. BARTLETT.
